UNITED STATES PATENT OFFICE.

ROY MILLS, OF CLARKSVILLE, TENNESSEE.

STAVE-JOINTING MACHINE.

Application filed November 12, 1923. Serial No. 674,347.

This invention relates to wood working machinery and the primary object of the invention is to provide an improved machine for forming barrel staves and the like, which is so constructed as to simultaneously cut both of the curved longitudinal edges of a barrel stave, properly proportion the curves of the edges to the width of the stave to secure the proper bilge to the barrel and bevel 10 the edges of the stave to insure the proper making of the radial joint between the assembled staves.

Another prime object of the invention is to provide in a stave forming machine, novel 15 means including an eccentrically mounted master bilge wheel for forcing the stave stock between a pair of oppositely inclined circular cutting tools, the master bilge wheel insuring the proper taper to the stave to 20 secure the bilge of the barrel by raising and lowering the stave stock between the oppositely inclined tools.

A further prime object of the invention is to provide in a stave forming machine, 25 novel means for guiding the stave stock through the machine during the sawing process and novel means for frictionally holding the stave stock in contact with the master bilge wheel.

30 A further object of the invention is the provision of an improved guide and indicator arranged on the stock table for indicating the angle of inclination and distance between the oppositely inclined circular saws, thereby facilitating the operation of 35 the machine and the cutting of the staves.

A further prime object of the invention is to provide novel means for synchronously 40 adjusting the guide and the saws, whereby the guides or indicators, will at all times indicate the distance between the saws irrespective of the adjustment thereof.

A further prime object of the invention is the provision of a latch for normally holding 45 the master bilge wheel in a predetermined position, so that the same will always be in proper position for guiding a new stave stock through the machine, and novel means for insuring the proper position of the bilge wheel in relation to the latch.

A still further object of the invention is to provide an improved stave forming machine of the above character, which will be durable and efficient in use, one that will be 55 simple and easy to manufacture and one

which can be placed upon the market at a reasonable cost.

With these and other objects in view, the invention consists in the novel construction, arrangement and formation of parts, as will 60 be hereinafter more specifically described, claimed, and illustrated in the accompanying drawings, in which:

Figure 1 is a side elevation of the improved stave forming machine.

Figure 2 is a top plan view thereof.

Figure 3 is a rear end elevation of the improved machine.

Figure 4 is a longitudinal vertical section through the improved machine taken on the 70 plane indicated by the line 4—4 in Figure 2 of the drawings showing a stave entering and leaving the machine.

Figure 4^a is a diagrammatic view showing the stave being raised for cutting the central 75 portion thereof.

Figure 5 is a fragmentary bottom plan view of the table for receiving the stock, illustrating the means for adjusting the guide and indicator.

Figure 6 is a vertical transverse section through the table of the machine taken on the line 6—6 of Figure 2.

Figure 7 is a detail sectional view illustrating the means for mounting one of the 85 traveling nuts on the feed screw or shaft for bringing about the adjustment of the saws, and

Figure 8 is a detail section through the feed screw or shaft looking in a direction 90 toward one of the feed nuts showing the means of connecting one adjusting lever with one of the nuts.

Referring to the drawings in detail, where in similar reference characters designate corresponding parts throughout the several views, the letter A generally indicates the frame of the improved stave forming machine; B the table for receiving the stave stock; C the means for cutting the stock; D the improved means for insuring the proper taper to the stave to secure the bilge of the barrel; E the novel means for guiding the stock through the machine; F the novel 100 guide and indicator for indicating at the table the distance between the members constituting the cutting mechanism C, and G the novel mechanism for synchronously operating the members constituting the cutting mechanism C and the guide and indicator F.

The frame A of the machine can be built in any desired way and of suitable timbers and as shown the same includes the upright supporting corner standards 10 connected at their lower ends by longitudinally extending brace beams 11 and at their upper ends by longitudinally extending brace beams 12. The corner standards 10 which are arranged in transverse alignment are connected together by upper and lower transverse beams 13 which are also connected to the upper and lower longitudinally extending beams 12 and 11. Disposed upon the upper longitudinally extending beams 12 are a pair of longitudinally extending spaced sills 14 on which are arranged the various parts of the stave forming machine.

The frame A also preferably includes diagonally extending brace beams 15 which extend downwardly and rearwardly from the front pair of corner standards 10 which are arranged in transverse alignment to the rear pair of corner standards 10.

The table B for receiving the stave stock consists essentially of a pair of spaced longitudinally extending supporting bars 16 which extend forwardly from the frame A and these bars 16 are secured in any desired way to the sills 14 and terminate short of the cutting mechanism C. The extreme rear ends of the bars 16 are connected together by a transverse connecting end bar 17. Secured to the upper surface of the bars 16 adjacent to the outer and inner ends thereof are arranged transversely extending supporting boards 18 and 19 which carry angle-shaped transversely extending guides 20. These transverse boards 18 and 19 receive the table top proper for the stock which includes a pair of movable table boards 22 and 21 which form a part of the guide and indicating means F, as will be hereinafter more fully described. The table boards 21 and 22 carry companion angle-shaped guides 23 for receiving the guide tracks 20. It thus can be seen that the boards 21 and 22 can be slid transversely of the machine relative to one another. A third table board 24 is provided, which can be rigidly secured to the supporting boards 18 and 19 if so desired.

The frame A also preferably includes circular cutting saws 25 and 26 of the desired diameter and these saws are disposed at an inclination to one another and to the longitudinal center of the machine. Each saw is mounted upon a saw mandrel 27 which is rotatably mounted in suitable bearings 28 carried by swinging blocks 30. The blocks 30 are mounted for swinging movement in suitable brackets 31 carried by each sill 14 at a point intermediate the ends thereof. The outer terminals of the saw mandrel 27 have keyed or otherwise secured thereto suitable pulleys 32 to permit the rotation of the circular saws 25 and 26. These circular saws

25 and 26 are disposed adjacent to the longitudinal center of the machine as can be clearly seen by referring to Figures 2 and 3 of the drawings.

The inner ends of the bearings 28 for the saw mandrels 27 have pivotally connected thereto as at 33 the upper ends of bell crank levers 34, which are pivoted at their angles to suitable brackets 35 connected to blocks 36 carried by the frame A. The lower ends 75 of the bell crank levers 34 are provided with yokes 36' for straddling traveling adjusting nuts 37 and 38. These traveling adjusting nuts 37 and 38 are provided with oppositely extending pins 39 which are fitted within the 80 slotted ends of the yoke 36'. These traveling adjusting nuts 37 and 38 are mounted upon the right and left-hand threaded portions of the adjusting screw 40 which is rotatably mounted in suitable bearings 41 carried by blocks 42 which can be secured to the diagonal brace beams 15 of the frame A. It is obvious that by rotating the feed screw 40 the traveling nuts 37 and 38 can be moved toward or away from each other according 90 to the direction of rotation of the said feed screw and the movement of the traveling nuts will change the inclination and the distance between the circular saws 25 and 26. This feed screw 40 is operated by the 95 means G for simultaneously adjusting the position of the saws 25 and 26 and the guide means F, as will be hereinafter more fully described.

The means D utilized for insuring the 100 proper cutting of the stave stock by the saws 25 and 26 comprises a master bilge wheel 45 which is eccentrically mounted on a rotatable shaft 46. This shaft 46 is rotatably mounted in suitable bearings 47 105 which can be mounted upon the blocks 36. Now it can be seen that the greatest distance between the saws 25 and 26 is adjacent to the upper end thereof and thus to cut the widest portion of the stave, the same will 110 necessarily have to be lifted adjacent to the upper ends of the saws. The master bilge wheel 45 has its axis located forwardly of and below the axis of the saws 25 and 26, but a portion of the wheel extends between 115 the saws at all times, as can be clearly seen by referring to Figures 2 and 3 of the drawings. Now when the master bilge wheel 45 is at its lowest point, it is obvious that the narrowest point of the staves will be cut. 120 The inclination of the saws 25 and 26 also provide the bevel on the edges of the staves, which is necessary, as well known to persons skilled in the art.

The stave stock is adapted to be fed 125 through the machine by novel guiding means E, which will be hereinafter more fully described. The circumference of the bilge wheel 45 is preferably less than the length of the stave stock being cut. This is to the 130

end that the wheel 45 will have completed one complete revolution when a stave has passed through the machine. It is necessary to have the lower point of the master bilge wheel 45 normally uppermost, so that the narrow front portion of the stave will be cut first and in order to insure that the lowest point of the wheel will be disposed uppermost, a suitable latch mechanism is provided. This latch mechanism can be of any preferred character or located at any desired point, but as shown in the drawings, I have provided a detent 47 which is pivotally mounted at a point intermediate its ends upon a supporting bracket 48. This detent is provided with a hooked end 49 which is normally urged into engagement with the periphery of the wheel 45 by means of a suitable weight or the like 50. A notch 51 is formed in the periphery of the wheel directly opposite the low point of the cam and the hooked end of the detent is adapted to fit within the notch. The wheel 45 forwardly of the notch 51 is weighted as at 52, and this weighted portion of the wheel normally tends to move the notch directly above the detent. Now the weighted portion 52 of the wheel 45 and the latch function in the following way. When the stock is fed through the machine onto the periphery of the eccentrically mounted master bilge wheel 45, the same will be rotated and as the circumference thereof is slightly less than the length of the stave being formed, the notch 51 will be moved past the detent 47. Now when the stave has passed through the machine, the weighted portion 52 of the wheel will tend to rotate the same in a retrograde direction and when the detent 47 snaps into the notch 51, further rotation of the wheel will be prevented and the wheel will be held in its normal position.

In order that the stock be held in frictional contact with the periphery of the eccentrically mounted master bilge wheel 45, a weighted transversely extended roller 55 is provided. The terminals of the roller 55 are provided with pintles 56, which are rotatably mounted in suitable bearing blocks 57, which are hingedly connected to supporting blocks 58, as at 59. The supporting blocks 58 are disposed upon the upper surface of the beams 16 of the table B directly forward of the saws 25 and 26.

The guiding means E for insuring the correct passage of the stock through the machine includes pairs of rollers arranged in front of the weighted roller 55 and pairs of rollers disposed in rear of the saw blades 25 and 26. The front pairs of rollers are mounted one in front of the other on the bars 16 of the table B. Each pair of the front rollers includes a lower roller 64 and an upper spring pressed roller 65 and the stock is adapted to travel between the upper

and lower rollers 64 and 65 of the front pairs of rollers. It can be seen that the upper rollers 65 of the front pairs of rollers have their pintles rotatably mounted in suitable blocks 66, which are slidably mounted within the bearing brackets and the blocks are engaged by expansion springs 67.

The rear pairs of guide rollers are constructed substantially the same as the front pairs of guide rollers with the exception that the rearmost pair of guide rollers is located slightly above the innermost pair of the rear pairs of guide rollers in order to receive the front of the stave, as the same is raised by the master bilge wheel. Each of the rear pairs of guide rollers includes a lower rotatable roller 68 and an upper sliding and rotatable roller 69. Bearing brackets 70 are provided for the rollers, which are mounted upon suitable blocks 71 secured to the sills 14. The pintles of the upper rollers 69 are mounted in sliding blocks 72 and expansion springs 73 bear against the blocks for normally holding the rollers 69 in engagement with the lower rollers 68. The tension of the springs 73 can be adjusted by any preferred means.

As the stock is cut by the saws 25 and 26, the same is guided into the first pair of the rear pairs of rollers by suitable guide pieces 74. These guide pieces 74 are of a substantially arcuate shape and are arranged one on each side of the outer faces of the saw blades 25 and 26 and are secured to any preferred part of the frame A by the use of suitable supporting brackets. The guide pieces 74 gradually curve upwardly and rearwardly to a point substantially between the upper and lower rollers 69 and 68 of the first pair of the rear pairs of rollers.

The front and rear pairs of rollers are driven synchronously by means which will now be described. A drive shaft 75 is rotatably mounted on the frame A and this shaft can be operated from any suitable source of power and is provided with a balance and drive wheel 76. This drive shaft is operatively connected to the lowermost roller 64 of the first pair of front rollers by means of a sprocket chain 77 which is trained about the wheels 78 and 79. These wheels are keyed or otherwise secured respectively to the shaft 75 and to one pintle of the lower roller 64. The upper and lower rollers 64 and 65 of the first pair of front rollers are operatively connected by intermeshing pinions keyed respectively to the pintles of the said upper and lower rollers 64 and 65. The lower rollers of the front pairs of the rollers are operatively connected through the medium of the sprocket chain 81, which is trained about the sprocket wheels 82 keyed respectively to the said lower rollers 64. The front pair of the rear pairs of rollers are driven through the me-

dium of the sprocket chain 83 which is trained about sprocket wheels 84 keyed respectively to the upper roller 65 of the first pair of front rollers and the upper rollers 69 of the rearmost pair of the rear pairs of rollers.

The upper and lower rollers 69 and 68 of the rearmost pair of the rear pairs of rollers are operatively connected together by means 10 of intermeshing pinions 85, which are keyed respectively to the said rollers 69 and 68. The lower rollers of the rear pairs of rollers are operatively connected to the medium of a sprocket chain 86, which is trained about 15 the sprocket wheels 87 keyed respectively to the pintles of the lower rollers 68 of the rear pairs of rollers.

The guiding and indicating means F for the stock disposed upon the table B consists 20 of a gage plate 90 which is disposed at one longitudinal edge of the table board 21 and the gage plate 90 is pivotally connected to the table board 21 through the medium of weighted arms 91 which are pivoted intermediate their ends to brackets 92 secured to the lower surface of the table board 21. An indicating pointer 93 is carried by the table board 22 and the point of this pointer 93 is in direct alignment with the right-hand saw 25 30 while the gage plate 90 is in direct alignment with the left-hand saw 95.

The table boards 21 and 22, carrying the gage plate 90 and the indicating finger 93, are adjusted through the medium of a feed 35 screw 94 which is rotatably mounted in suitable bearings 95 carried by a cross brace bar 96. This cross brace bar 96 is held in place by suitable depending hangers or straps 97 which are secured to the inner 40 faces of the longitudinally extending beams 16 of the table B. By referring to Figures 5 and 6 it can be seen that the feed screw 94 is provided both with right and left-hand threads and that right and left-hand traveling nuts 98 and 99 are mounted upon the feed screw. The traveling nuts 98 and 99 have secured thereto supporting arms 100 and 101 respectively and the arms 100 and 101 are in turn respectively secured to the 45 table boards 21 and 22. By rotating the feed screw it can be seen that the table boards 21 and 22 can be moved toward and away from each other according to the direction of rotation of said feed screw and that 50 the gage plate 90 and indicating finger 93 can consequently be moved toward and away from each other.

The means G for bringing about the synchronous operation of the indicating means 60 F and the saw blades 25 and 26 comprises an inclined operating shaft 102, which is mounted in suitable bearings carried by the table top and frame A. One end of the shaft 102 is provided with a hand-controlled wheel 103 which permits the easy rotation

of said shaft. This hand wheel 103 is located adjacent to the forward end of the table B. A beveled gear 104 is keyed to the shaft 102 and meshes with a beveled gear 105 keyed or otherwise secured to the feed screw 94. Adjacent to the rear end of the controlled shaft 102 is keyed or otherwise secured thereto a beveled gear 106 which meshes with a beveled gear 107 keyed or otherwise secured to the feed screw 40 for 75 the saws.

By this construction it is obvious that any change in the position of the saw will be shown on the table top through the medium of the gage plate 90 and the indicating finger 93. A scale is not shown on the table-board 21 to indicate the amount of separation of the saws but a scale may be used if desired. This distance is determined by the eye, or by the use of a suitable measuring instrument.

In operation, the stock to be cut is placed on the table top B against the gage plate 90 and the hand-wheel 103 is turned so as to adjust the saws to the size of the stock and for the end width of the stave to be cut. The machine is now set in operation and the stock is fed through the pairs of rollers 60 and 61 by hand and under the weighted roller 55 and on top of the master bilge wheel 45. The rollers will now effectively feed the staves forwardly and the saws 25 and 26 will commence cutting the staves. As the stave is fed through the machine the master bilge wheel 45 will be turned which will gradually raise the stock and thus permit the saws to cut the widest portion thereof. After the bilge wheel has made one half of a revolution the stock will then be gradually lowered and thus the saws will 100 cut the tapered rear end thereof. As the stock leaves the saws, the same will be guided to the first pair of rear rollers through the medium of the guides 74 and thence out of the machine by the rear pair of rollers. When the stock leaves the saws, the bilge wheel will have made slightly more than one revolution and the weighted portion thereof will rotate the bilge wheel slightly in a retrograde position until the latch engages the notch therein, which will hold the bilge wheel in its normal position for engaging the next piece of stock to be cut.

From the foregoing description, it can be seen that I have provided an exceptionally simple and durable machine for effectively making barrel staves and the like which will give the correct curvature to the longitudinal edges of the stave and the proper bevel thereon.

Changes in details may be made without departing from the spirit or the scope of this invention.

What I claim as new is:

1. In a stave forming machine, a frame,

and a pair of angularly related circular saws, blocks pivotally secured to the frame for supporting the saws, bell crank levers pivoted at their angles to the frame, means 5 pivotally connecting the upper ends of the bell crank levers to the means for supporting the saws, a transverse feed screw having right and left-hand threads formed thereon, traveling nuts mounted upon the right and 10 left-hand threads, means connecting the lower ends of the bell crank levers to the nuts, a table for initially receiving the stave stock secured to the frame including a pair of sliding table boards, a gage plate carried 15 by one table board normally in alignment with one saw blade and an indicating finger carried by the other table board normally in alignment with the other saw blade, a second feed screw having right and left- 20 hand threads formed thereon, traveling nuts mounted upon the right and left-hand threads of the second mentioned feed screw, arms rigidly connecting the boards with the last mentioned nuts, an operating shaft rotatably carried by the frame, and a hand- 25 wheel carried by one end of the shaft, and beveled gearing operatively connecting the

shaft to both of said feed screws, as and for the purpose specified.

2. In a stave forming machine, a frame 30 and a pair of angularly related circular saws, blocks pivotally secured to the frame for supporting the saws, a table arranged in front of the saws for initially receiving the stave stock secured to the frame including a 35 pair of sliding table boards, a gage plate carried by one table board normally in alignment with one saw blade and an indicating finger carried by the other table board normally in alignment with the other saw blade, 40 a transversely extending feed screw having right and left hand threads formed thereon, travelling nuts mounted upon the right and left hand threads of the feed screw, arms rigidly connected to the boards and with 45 the nuts, a longitudinally extending operating shaft rotatably carried by the frame, bevel gearing operatively connecting the operating shaft with the screw, means operatively connecting the operating shaft with 50 the supporting blocks for the saws, and means for actuating said operating shaft.

In testimony whereof I affix my signature.
ROY MILLS.
